(57) **CLAIM**

The ornamental design for an LED lighting cosmetic mirror, as shown and described.

DESCRIPTION

FIG. 1 is a front, top, right perspective view of an LED lighting cosmetic mirror showing my new design;

FIG. 2 is a rear, top, left perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is an enlarged view of the circled portion "18" of FIG. 1.

The broken lines in the figures are included for the purpose of illustrating portions of the article which form no part of the claimed design.
